UNITED STATES PATENT OFFICE.

EMANUEL W. SUNDBERG, OF ST. LOUIS, MISSOURI, ASSIGNOR TO WAGNER ELECTRIC MANUFACTURING COMPANY, OF ST. LOUIS, MISSOURI, A CORPORATION OF MISSOURI.

CONTROLLER-REGULATOR.

1,252,732.

Specification of Letters Patent.

Patented Jan. 8, 1918.

Application filed June 21, 1916. Serial No. 104,865.

To all whom it may concern:

Be it known that I, EMANUEL W. SUNDBERG, a citizen of the United States of America, residing at the city of St. Louis, 5 State of Missouri, United States of America, have invented a certain new and useful Controller-Regulator, of which the following is such a full, clear, and exact description as will enable any one skilled in the art to 10 which it appertains to make and use the same, reference being had to the accompanying drawings, forming part of this specification.

My invention relates to a handle particularly applicable as means for operating starting controllers for electric motors.

It is well known that when starting a motor it is usually desirable to allow the starter handle to dwell in at least one starting position for a certain time before moving it on to the next step, and it is the object of my invention to provide means which will force the operator to stop for a short period of time as soon as he has 25 brought the handle of a starter from the "off" to the starting position, thus giving the motor a chance to reach a sufficiently high speed before the handle is moved to the next starting, or to the running, position.

Referring to the accompanying drawings, Figure 1 is a front elevation, and Fig. 2 is a side elevation of one embodiment of my invention. Fig. 3 is a view of the locking 35 mechanism in the direction of arrow A of Fig. 2. Fig. 4 is a cross-section on line 14 of Fig. 1. Fig. 5 shows one relative position of parts of the locking mechanism. Fig. 6 is a view of certain details.

Referring to the drawings, the lever 3 is 40 keyed to the shaft 2 controlling the contact mechanism of the starting switch, and is provided with a handle 4. This lever is shown in its "off" position in Fig. 1. If it 45 is moved to the left, through an angle of about 14 degrees, the switching mechanism is placed in the starting position (line 15). When the handle 4 is moved in the same direction, through a further angle of 22 degrees, the switching mechanism occupies the 50 running position (line 16). In order to prevent the operator from moving the lever 3 from the position 14 to the position 16 without stopping at the position 15, the 55 mechanism now to be described is provided.

A pin or stop 7 attached to a lever 20 pivoted on the controller case 13 at 19 is arranged to enter a cavity 25 provided on the lever and best shown in Fig. 3. Said cavity contains a guiding pawl 8, best shown 60 in Fig. 6, pivoted on the screw 6 and under the control of a spring 5 attached to the lever 3 at 12. This spring tends to hold the pawl in the position shown in Figs. 1, 3 and 5. The lever 3 is connected to the shaft 2, and it cannot be moved parallel thereto; and the pin 7 pivoted on the stud 19 and movable to an extent limited by the shoulder 21, cannot move in a direction parallel 65 to the axis of said stud or of the shaft 2. 70 The free end of the pin 7 can, therefore, never come into contact with the inner wall of the cavity 25 or with the facing 9 or the spring 5 of the pawl 8, but it does coöperate with the projection 10 of the pawl 8, as is 75 best seen in Figs. 4 and 6. The cavity 25 is limited by an inner wall, side walls, a bottom wall or supporting flange, and an outer wall, the latter only covering a very 80 small part of the cavity, as shown in the portion of Fig. 3 indicated at 26. The side walls of the cavity 25 are provided with two openings 17 and 18 through which the pin 7 may enter or leave the cavity. The path which the pin 7 may take through said 85 cavity depends on the direction in which the handle 4 is moved, and is controlled by the projection 10 of the pawl 8.

The operation of the device is as follows: 90 When the handle is in the "off" position, as shown in Figs. 1 and 3, the pin 7 rests on the supporting flange 24 and lies in the neighborhood of the opening 17. As the operator moves the handle from position 14 to position 15, the pin slides on the flange 95 24 until it strikes the projection 10 of the pawl 8, when it rides over the back of said projection until it has reached the highest point thereof. If the operator continues to propel the handle in the same direction, the pin 7 will ride over the top of the pawl 8 and, when the handle reaches the position 15, said pin will be clear of the projection 10 of the pawl 8 and will drop, owing to its weight, swinging about the stud 19. The 100 path the pin 7 can take under the influence of gravity when the handle reaches the position 15, is indicated in Fig. 5 by the arcs of circles 22 and 23, and it is seen that the pin will strike the outer wall of the cavity 105 110

which is located just above the opening 18. Should the operator attempt to push the handle beyond the position 15, even after having stopped there, it is clear that he will be prevented from doing so by the side-wall referred to which acts as a stop. He can only disengage or free the lever from the control of this pin by moving the handle back toward the position 14 through a small angle. This angle depends on the configuration of said side-wall and is increased when a shoulder, such as 27, is added. When the operator moves the handle back, the pin 7 still pivoting about the stud 19, will drop within the cavity until it reaches the bottom wall or flange 24 on which it will rest until the handle is again pushed in the direction of the running position 16, when the pin 7 will leave the cavity by the opening 18, and the lever 20 will come to rest on the shoulder 21.

When returning the handle to the "off" position, the pin 7 will be picked up as soon as the flange 24 of the cavity 25 comes into contact with said pin, and the latter will ride on this flange until it strikes the inside and lower part of the projection 10 of the pawl 8. The movement of the handle being continued in the direction of position 14, the pin 7 will force the pawl 8 out of contact with the flange 24, pass under the nose of the pawl, and finally reach its original position, or that indicated in Figs. 1 and 3, when the pawl will snap back into its original position under the influence of the spring 5.

Having fully described my invention, what I claim as new and desire to secure by Letters Patent of the United States is:

40 1. The combination of a controller and operating lever therefor, a pivotally mounted element provided with a stop coöperating with the lever, a guide adapted upon forward movement of the lever to bring the stop into a position to limit said movement, and means preventing the release of the lever for further forward movement until same has been moved backward to a certain extent.

50 2. The combination of a controller and operating lever therefor, a pivotally mounted element provided with a stop coöperating with the lever, a pivoted guide adapted upon forward movement of the lever to bring the stop into a position to limit said movement, and means causing said stop to pass under the pivoted guide upon the backward movement of the lever from a running position to its "off" position.

60 3. The combination of a controller and operating lever therefor, a pivotally mounted element provided with a stop, a flange on the lever for supporting and guiding said stop, a stop on the lever, a pivoted guide having one end adjacent to said flange and

adapted to raise the pivotally mounted stop into engagement with the stop on the lever upon forward movement of said lever to a predetermined extent, said pivotally mounted stop being free to drop to the supporting flange and out of engagement with the stop on the lever upon a short backward movement of said lever, and said flange and pivoted guide being so positioned relatively to each other that the pivotally mounted stop will pass over the pivoted guide when the lever is moved from "off" position to a running position and under the guide when the lever is returned to "off" position.

4. The combination of a controller and operating lever therefor provided with a stop, a controlling element carried on a stationary pivot and provided with a stop slidably supported on the lever, means carried by said lever for bringing said stops into engagement upon the forward movement of the lever, and means preventing the disengagement of said stops except upon a short backward movement of the lever.

5. The combination of a controller and operating lever therefor provided with a stop, a controlling member provided with a stop, means for bringing said stops into engagement upon forward movement of the lever, said means being adapted to pass under the last mentioned stop during the movement of the lever in one direction and over said stop during the movement in the opposite direction.

6. The combination of a controller operating lever, a controlling member provided with a stop coöperating with said lever, means on the lever providing two passage-ways for the stop, one of said passage-ways being tortuous to prevent uninterrupted forward movement of the lever from "off" to running position and the other passage-way being free from means to interrupt the return movement of the lever.

7. The combination of a controller, an operating lever therefor, a pivoted controlling lever provided with a stop, and a flange and a pivoted cam on the operating lever, both adapted to coöperate with the stop on the controlling lever.

8. The combination of a controller, an operating lever therefor, means controlling the movement thereof comprising a pivoted controlling lever provided with a stop, a flange on the operating lever for supporting and guiding the stop, and a cam carried by the operating lever adapted to raise the stop from the flange and bring it into position upon the forward movement of the lever to limit the motion thereof.

9. The combination of a controller, an operating lever therefor provided with a pivoted cam, a stop, and a flange extending beneath the cam and stop; a pivoted controlling element provided with a stop adapt-

ed to rest on the flange of the lever in the "off" position of said lever and to be raised by contact with the upper surface of said cam and brought into engagement with the stop on the lever upon the forward movement of said lever to a predetermined extent; and means beneath the stop on the lever to support the stop on the controlling element, said means and cam being positioned to provide a passage-way whereby the stop on the controlling element may drop from engagement with said means to the flange upon a short backward movement of the

lever, and said flange being positioned to guide the stop on the controlling element ¹⁵ under the pivoted cam upon movement of the lever from a running position to its "off" position.

In testimony whereof, I have hereunto set my hand and affixed my seal in the presence ²⁰ of the two subscribing witnesses.
